RAIL SLEWER IN COMBINATION WITH THRUST RAILS

Application filed April 20, 1931, Serial No. 531,592, and in the Netherlands May 27, 1930.

The invention relates to a rail slewer of very simple construction and has for an object to provide means for correcting the gaps at the joints, for bringing the joints of a leading line of rails into proper relation to the joints of the opposite line and for replacing creeping rails into their original positions.

In the use of prior rail slewers operating by means of wedges, right and left hand screw rods or the like, it is necessary to loosen the bolts between the fish plates and the rails and the connections between the rails and the sleepers. These operations require a great deal of time and such rail slewers are less adapted for portions of a line having a lively traffic.

It is an object of the present invention to overcome the above disadvantages. According to the invention the rail slewer comprises a U-shaped body and a wedge and the side portions of the U-shaped body form an angle which corresponds to the angle of the wedge, so that the rail may be clamped between one side portion and the wedge. When the rail slewer is to be used the U-shaped body is applied sideways to the rail so that one side portion engages the lower side of the rail foot and the wedge is inserted between the other side portion of the U-shaped body and the rail head. Then the projecting end of the wedge is hammered or rammed in longitudinal direction. After a few strokes the rail will be securely clamped between the wedge and the U-shaped body so that further strokes will result in a displacement of the rail or line of rails.

Preferably a thrust bar is used for the operation of the rail slewer. This thrust bar may be mounted on rollers so that it is adapted to being easily moved forwards and backwards over a line of rails.

The advantages of such a thrust bar over a hammer will be readily understood from the following. A thrust bar will always strike

exactly the same spot of the head of the wedge and a correct finishing of the co-operating faces of the thrust bar and the wedge will allow these faces to contact over their entire surfaces. Accordingly the material of the wedge will not be perceptibly deformed and the entire quantity of kinetic energy which has been accumulated in the thrust bar before the stroke will be available for the displacement of the rail, no kinetic energy being wasted for the deformation of the wedge. Furthermore, the direction of the stroke coincides exactly with the direction of the rail. In using a sledge hammer succeeding strokes will hit different spots on the head of the wedge, the co-operating faces of the wedge and the hammer being relatively small. Accordingly the head of the wedge will be deformed. The stroke of the hammer will never coincide accurately with the longitudinal direction of the wedge, the latter being shifted at each stroke. It is obvious that the deformation and the shifting of the wedge will result in a waste of energy.

The rail slewer according to the invention is adapted to being readily positioned and removed and to being applied with the same result to rails of different cross sections.

Further objects and particulars of the invention will be apparent from the following description of the accompanying drawings, wherein:

Fig. 1 is a front elevation of a rail slewer according to the invention in mounted position together with a thrust bar;

Fig. 2 is a side elevation of the rail slewer taken on the line II-II of Fig. 1, the wedge being shown in cross section;

Figs. 3 and 4 illustrate an interchangeable filling plate in longitudinal section and side elevation respectively.

The U-shaped body 1 is preferably made from forged steel and is provided with ears 2 which have been welded to the body. The ears are provided with holes 3 through which

a bar may be passed for transporting purposes.

The length of the wedge 4 is about twice that of the U-shaped body 1, so that when using the rail slewer for rails of different heights contact between the wedge and the U-shaped body over the entire length of the latter is always ensured.

The upper and lower inner surfaces of the side portions of the U-shaped body and the contacting surfaces of the wedge have been planed, filed or milled. The width of the lower surface is determined by the greatest width of the foot of the rails to be handled; the upper surface need not be much wider than the wedge. The acute angle between the finished surfaces of the U-shaped body corresponds to the angle between the cooperating surfaces of the wedge.

To prevent rotation of the rail slewer about a vertical axis during operation the free end of the lower side portion of the U-shaped body may be provided with an inwardly directed flange 5 which determines the maximum width of the rail foot. However when rails are to be handled having feet which are smaller than the lower surface, a filling plate 6 may be laid over the lower surface. This plate 6 is provided with a longitudinal groove having a width corresponding to that of the rail foot. The flanges 7 secure the plate in correct position. The wedge is guided between the vertical portion of the U-shaped body and an inwardly directed flange 8 at the free end of the upper side portion.

In Fig. 1 the complete arrangement of the rail slewer and a thrust bar 9 mounted on two or more rollers 10 is illustrated. In practice this rail slewer has fully satisfied the requirements. It can be easily handled and can withstand the severest strain without being damaged, because it only comprises two almost unbreakable parts.

What I claim is:-

1. A rail slewer comprising a body having a U-shaped cross section and a wedge, characterized in that the side portions of this body form an angle which is equal to the angle of the wedge, so that the rail may be clamped between one side portion and the wedge which is guided by the other side portion and is rammed or hammered in the operation of the device.

2. A rail slewer according to claim 1 in combination with a thrust bar which is mounted on rollers and is adapted for being rolled backwards and forwards over a line of rails.

3. A rail slewer comprising a body having a U-shaped cross section and a wedge, characterized in that the side portions of this body form an angle which is equal to the angle of the wedge, so that the rail may be clamped between one side portion and the

wedge which is guided by the other side portion and is rammed or hammered in the operation of the device and each side portion being provided at its free end with an inwardly directed flange.

4. A rail slewer according to claim 3, characterized in that an interchangeable filling plate is provided at the inner side of one side portion, this plate being provided with a longitudinal groove having a width corresponding with that of the foot of the rail.

In testimony whereof I affix my signature.
